UNITED STATES PATENT OFFICE.

CLAUDE ELLIS, OF SPRINGVILLE, NEW YORK.

WINDOW SCREEN AND SASH LOCKER.

1,425,515.

Specification of Letters Patent. Patented Aug. 15, 1922.

Application filed June 3, 1921. Serial No. 474,644.

To all whom it may concern:

Be it known that I, CLAUDE ELLIS, a citizen of the United States, residing at Springville, in the county of Erie and State 5 of New York, have invented a new and useful Improvement in Window Screen and Sash Lockers, of which the following is a specification.

This invention relates to window screen 10 or sash locks of the general type shown in United States Letters Patent No. 1,360,628 issued to me November 30, 1920.

As illustrated in the patent, devices heretofore proposed for the purpose of locking 15 a screen in position beneath a window sash and locking the sashes together so as to prevent opening of the sash or removal of the screen, have consisted of parts operating on a screw rod or the like so as to be 20 extended or contracted to fit windows of different sizes. With such devices, when it is necessary to materially vary the length of the rod for use with different windows or with screens of different sizes, consider- 25 able time is required to actuate the parts on the screw rod to lengthen or shorten the device. Furthermore, owing to accumulations of dust or other deposits in the threaded rod and the adjusting nuts such devices be- 30 come very difficult of adjustment and cannot be lengthened or shortened without the use of suitable tools, and the provision of screw rod connections and the like makes the de- 35 vices relatively expensive.

The objects of this invention are to pro- 35 vide a portable lock consisting of few parts, which is inexpensive of manufacture; also to provide a lock of the type set forth which may be most readily and quickly adjusted 40 to lock window sashes and screens of vary- ing sizes; and also to provide a lock having parts which are freely movable to vary the length of the device and which require no tools for effecting such adjustment. Further 45 objects are to improve window screen and sash locks in the other respects herein- after described and claimed.

In the accompanying drawings:

Fig. 1 is a sectional perspective view of a 50 window provided with a sash and screen lock constructed in accordance with the present invention.

Fig. 2 is a sectional elevation thereof.

Fig. 3 is an elevation of the screen and 55 sash locking device in one adjusted position.

Fig. 4 is a sectional elevation of the de- 60 vice in another adjusted position.

Fig. 5 is a top plan view of the locking 65 device.

The invention, generally stated, comprises an extensible member consisting of two tele- 70 scoping parts, one of which parts is provided with a portion adapted to engage a frame of an upper sash of a window and the other 75 part being adapted to engage the frame of a lower sash of a window. The invention also includes means for releasably securing said telescoping parts in different positions.

A and B designate respectively the up- 75 per and lower sashes of a window and C 80 designates a metal or wire screen positioned in the window casing below the lower sash. D designates the frame of the lower sash B, and E designates the frame of the upper 85 sash A. These parts are of any of the usual well known constructions and form no part of the present invention.

10 and 11 designate the telescoping parts 85 of the improved sash and screen lock. In 90 the embodiment illustrated, the member 10 is in the form of a rod, which may be formed of wood, soft metal or other suitable mate- 95 rial, and the member 11 is in the form of a sleeve or cap member of suitable length 100 arranged to slide upon the rod 10 so as to permit of variations in the length of the locking device. It is preferred to construct the rod 10 of wood so that the rods may be readily cut to the required length. In this 105 manner the devices may be manufactured and sold with wooden rods of one or more standard lengths and an end of the rod trimmed off by the user as necessary to fit any particular window or according to the 110 height of the screens used. In this manner with the minimum length of the device de- 115 termined by the amount the rod is trimmed off, the rod may be readily lengthened by adjusting the sliding sleeve 11. The sleeve 11 is adapted to slide freely on the rod 10 so that the device may be most quickly ad- 120 justed to the desired length. The sleeve 11 is provided with a laterally projecting 125 finger or tongue 12 which is adapted to en- 130 gage beneath the frame E of the upper sash. For purposes of providing a most strong 135 and rigid device this finger 12 is preferably 140 rigid or integral with the sleeve 11.

Means are provided for releasably secur- 145 ing the telescoping parts together and pre- 150 venting relative movement between them in

any of their adjusted positions. The preferred means for this purpose constitute a thumb screw 13 or the like which projects through and is threaded into the sleeve 11 and engages a portion of the rod 10 within the sleeve. In the preferred construction shown, the sleeve 11 is provided on one side with a boss 14 or lug having a screw threaded opening therethrough, thus providing a threaded opening of materially greater thickness than the walls of the sleeve, for the set screw. The lower end of the rod 10 engages frame D of the lower sash and is preferably provided with a resilient cushion or button 15 whereby when the device is in place the frame will not be marred and at the same time the device will be prevented from slipping from the frame. This resilient cushion or button also permits of easy intentional removal of the locking device from the inside of the window without changing the adjustment of the device, as the device may be pulled out laterally, the resilient cushion being readily compressed to permit disengagement of the finger 12 from the upper sash. The device may likewise be replaced in locking position without changing the adjustment. The locking device seating upon the upper frame of the lower sash and having the laterally projecting finger engaging the frame of the upper sash prevents the lower sash from

being raised to permit the screen to be removed and prevents the upper sash from being lowered, thereby effectively securing 35 the screen and sash against movement.

I claim as my invention:

1. In a sash and screen locking device, the combination of two telescoping members, a rigid laterally projecting integral finger carried by one of said members and adapted to engage a frame of a window sash, and releasable means for securing said members together in different extended positions, an end of the other of said members being adapted to engage the frame of another window sash. 40

2. In a sash fastener, the combination of a pair of telescoping parts, an integral laterally projecting finger on the outer end of one of said parts, and means for releasably securing said telescoping parts together and preventing relative movements between said parts in different extended positions. 45

3. In a sash fastener, the combination of a pair of telescoping parts, an integral laterally projecting finger on the outer end of one of said parts, means for releasably securing said telescoping parts together and preventing relative movements between said parts in different extended positions, and a resilient button at the outer end of one of said parts. 50 55 60

CLAUDE ELLIS.
